(57) **CLAIM**

The ornamental design for a tube securement device, as shown and described.

DESCRIPTION

FIG. 1 is a perspective view showing the new design for a tube securement device;

FIG. 2 is a front view thereof;

FIG. 3 is a back view thereof, wherein the stippling shown indicates adhesive;

FIG. 4 is a right side view thereof;

FIG. 5 is a left side view thereof;

FIG. 6 is a top view thereof; and,

FIG. 7 is a bottom view thereof.

The surface shading illustrated in the drawings is provided merely to highlight the contour of design; it is not intended to be illustrative of texture or gloss.

1 Claim, 2 Drawing Sheets
